UNITED STATES PATENT OFFICE.

EDWIN B. STIMPSON, JR., OF BROOKLYN, NEW YORK.

DESIGN FOR TRIMMING.

SPECIFICATION forming part of Design No. 18,769, dated November 27, 1888.

Application filed October 1, 1888. Serial No. 286,891. Term of patent 3½ years.

To all whom it may concern:

Be it known that I, EDWIN B. STIMPSON, Jr., of the city of Brooklyn, in the county of Kings and State of New York, have invented and 5 produced a new and original Design for Trim-
mings, of which the following is a specification.

My design is especially intended for trim-
mings made of leather.

I will describe my design in detail, and then
to point out the novel features in the claim.

The accompanying drawing illustrates my
design.

My design consists, essentially, of a row of
circles, *a*, and intermediate circles, *a'*, which
15 intermediate circles are so arranged as to form
a generally circular figure, *b*. I have shown
five of the circular figures *a'* so arranged as
to form the circular figure *b*, and one circular

figure *a'* arranged about centrally within said
five figures. The figures *a b* are arranged so 20
as to form a row of figures. Outside of the
rows of circular figures I have shown scallops
c of alternate angular and curved outline,
whereby points and semicircles are formed.

What I claim as my design is—

In the design for trimmings, the combina-
tion, with a row of circles *a*, of circular figures
intermediate of the circles *a*, said intermediate
figures being composed of circles and scallops
outside said row of circles, substantially as 30
shown.

EDWIN B. STIMPSON, JR.
